ELECTRIC LAMP SWITCHING MECHANISM

Robert C. Morton, Los Angeles, Calif., assignor to California Computer Products, Inc., Downey, Calif., a corporation of California

Application May 27, 1957, Serial No. 661,903

5 Claims. (Cl. 315—272)

The present invention relates to switching mechanisms for electric lamps, and it relates more particularly to such mechanisms which are controllable to provide a plurality of illumination levels from such a lamp.

The desirability of controllable artificial illumination in the average home and in other types of dwellings and environments is well established. Generally, different light intensities are required for reading, general conversation, television viewing and for other different activities.

Despite the widespread desire and need for inexpensive and practical dimmer or illumination switching mechanisms which would be compatible with standard light bulbs and lamps, however, such circuits prior to the present invention have failed to materialize to any appreciable extent. Instead, multi-element lights have been used with associated complicated and relatively expensive sockets and switching circuits, these general arrangements being such that the elements in the lights are selectively energized for different illumination levels.

The use of a controllable series resistance element in circuit with an ordinary single-element lamp bulb would provide the desired illumination control. However, such an arrangement is wasteful of energy and produces heat. Most fire codes prohibit the use of such series resistance elements. Inductive and capacitive series elements would not create the heat problem. However, these latter elements would be large and expensive. Also, such series impedance elements suffer from the disadvantage that the light reduction ratio depends upon the wattage of the light bulb used. This latter factor is manifestly undesirable. It is for these reasons that the prior art has for the most part turned to the unwieldy and unduly complicated switching arrangements described above.

A feature of the present invention is the provision of an assembly and mechanism which utilizes a minimum of components which, in themselves, are relatively inexpensive, and yet which provides a most convenient control for any standard single-element lamp in any standard receptacle or socket so as to establish at least two illumination levels from the lamp.

The invention is predicated upon rectification principles. In the mechanism of the invention, a rectifier is selectively switched in and out of the energizing circuit of a standard lamp and receptacle. When the rectifier is out of the circuit, the alternating current is directly applied to the lamp and the lamp glows with normal illumination intensity. However, when the rectifier is switched into the circuit, the illumination drops to roughly one-half its original value.

This use of a series rectifier in the energizing circuit of an electric lamp does not create any appreciable heat at the rectifier when it is in the circuit. There is, therefore, no increased fire hazard due to the use of the invention. Also, the rectifier itself may be a relatively inexpensive dry rectifier. This dry rectifier, for example, may be composed of silicon or germanium, or any other semiconductor material suitable for use in such rectifiers. The rectifier itself may be switched in and out of any present day lighting circuit in a most simple manner.

A major object of the invention, therefore, is to provide a simple and expeditious switching mechanism for a standard single-element electric lamp of any desired size or rating, by which the illumination of the lamp may be conveniently controlled between at least two distinct values. As noted above, a feature of the invention is that the mechanism may be incorporated into any existing lighting circuit and in that it does not require special light bulbs or fixtures.

10 As will be described, the invention may be incorporated in a typical wall switch control for the main lighting fixtures in a room, for example. Moreover, the invention may be incorporated into a lamp fixture to adapt the lamp to control the illumination of a conventional single-element light bulb inserted into a usual receptacle or socket in the lamp.

In the drawings:

Figure 1 is a perspective, somewhat schematic, view of a lamp receptacle which is constructed to incorporate a rectifier in accordance with the invention, and which also incorporates a single-pole double-throw actuating switch for providing two levels of illumination from a standard lamp bulb that is inserted into a standard socket forming a portion of the receptacle;

25 Figure 2 illustrates a wall switch arrangement in which a pair of wall switches are used respectively to control the energizing of an electric lamp and the level of illumination from the lamp; and

30 Figures 3 and 4 are electric control circuits illustrating suitable electrical connections for the respective embodiments of the invention shown in Figures 1 and 2.

The receptacle assembly of Figure 1 includes a socket 10 which may be a standard screw socket and which is adapted to receive a light bulb 12. The socket and light bulb are shown merely in schematic form. It is believed that the actual configuration of the socket 10 which may be a standard screw-type lamp socket, and of the light bulb 12 which may be a usual screw-base bulb, are exceedingly well known to the present day art. For that reason, a detailed and actual representation of these elements is believed to be unnecessary.

35 Mounted in the receptacle assembly of Figure 1 is a half-wave rectifier 14. The rectifier may be supported by any appropriate bracket means within the receptacle, or it may be embedded in the wall of the receptacle in the illustrated manner. The rectifier preferably is a dry-type half-wave rectifier. Such rectifiers are extremely well known and are readily procurable on the present market.

40 A single-pole three position switch 16 is also mounted in the receptacle of Figure 1 in any appropriate manner. The switch 16 may be of usual construction, and it has a center shaft 18 extending radially outward from the receptacle. The shaft 18 has an actuating knob 20 mounted on its outer end. The switch has a usual armature 22, and it has a first fixed contact 24 and a second fixed contact 26.

45 Electrical connection is established to the armature 22 of the switch through a contact 28. The switch is of known construction and it operates in a manner such that when the knob 20 is rotated, the armature 22 is snapped between the contacts 24 and 26 and an "off" position. In one operating condition of the switch, electrical connection is established through the armature 22 between the contact 28 and the contact 24. In a second operating condition of the switch, electrical connection is established through the armature between the contact 28 and the fixed contact 26. When the switch is in its "off" position its armature is out of engagement and contact with either of the fixed contacts 24 and 26.

50 70 A pair of leads 30 and 32 are connected respectively to the contact 28 and to one terminal of the socket 10. This terminal of the socket being adapted to be connected

to one terminal of the lamp bulb 12 when the bulb is screwed into the socket. These leads may be in the form of a usual electric cord, the cord having a socket at its remote end to be plugged into a receptacle connected to the usual alternating current mains. The receptacle of Figure 1 may be supported on any desired type of supporting bracket to constitute a floor or table lamp, and the cord formed by the leads 30 and 32 may extend down the interior of the supporting bracket.

One of the terminals of the rectifier 14 is connected to the fixed contact 24 of the switch 16. The other terminal of the rectifier is connected to the fixed contact 26 of the switch and to the other terminal of the socket 10. This other terminal is connected to the other terminal of the lamp 12 when the lamp is inserted in the socket.

The connections of the assembly of Figure 1 are more clearly shown in the electric circuit of Figure 3. It will be seen from the electric circuit of Figure 3 that when the switch 16 is at its illustrated neutral or "off" position, the lamp 12 is de-energized. However, when the armature 22 of the switch is moved to the fixed contact 26, the lamp bulb 12 is connected directly across the alternating current supply. Now, the full value alternating current is passed through the lamp 12 and it glows with a relatively high illumination value.

However, when the armature 22 of the switch 16 is moved to the fixed contact 24, the rectifier 14 is interposed in the circuit in series with the lamp 12. This rectifier provides a half-wave rectification of the current flowing through the lamp. The resulting unidirectional current pulses deliver approximately one-half of the original power to the lamp bulb 12. Therefore, when the switch 16 is in the latter operating position, the intensity of illumination by the lamp 12 drops to a relatively low value.

Thus, by the switching mechanism including a relatively simple switch and a small and inexpensive half-wave rectifier, a standard single-element light bulb in a standard socket may be controlled to have two distinctly different illumination levels.

In the embodiment of Figure 2, the switching mechanism includes a double-element wall switch 50, together with a half-wave rectifier 52 to provide two levels of illumination to a lamp 54. The wall switch unit includes a first switching element 56 and it further includes a second switching element 58. Each of these switching elements is of the usual single-pole single-throw type. The half-wave rectifier 52 may be a usual type of silicon dry rectifier, or the like, as described above.

The switching element 56 has a pair of screw-type terminals 60 and 62, and the half-wave rectifier 52 is connected across these terminals. The switching element 58 has a pair of similar screw-type terminals 64 and 66. The terminal 64 is connected to the terminal 62, and the terminal 60 is connected to one terminal of the lamp 54. The other terminal of the lamp 54, and the terminal 66 of the switching element 58 are connected to respective ones of the input terminals 68. These input terminals are adapted to be connected to the usual alternating current mains.

The connections of the mechanism of Figure 2 are more clearly shown in the electric control circuit of Figure 4. When the switch 58 is open, the energizing circuit to the lamp 54 is broken and the lamp is extinguished. When the switch 58 is closed and the switch 56 is opened, the energizing circuit to the lamp 54 is established through the rectifier 52. The lamp, therefore, glows at a relatively low illumination level. When the switch 58 and the switch 56 are both closed, the lamp 54 is connected directly across the alternating current main. Then, and for the reasons described above, the lamp glows at a relatively high illumination level.

It will be appreciated that it is a relatively simple matter to connect the dual switch 50 into any existing household circuit. Then, and without the need to change

any of the other circuit elements or connections, a convenient control circuit is provided for any desired location or room. Simply by operating the switch 58, the light 54 may be turned on or off. Then, by the manipulation of the switch 56, the light 54 may be turned bright or dim.

As noted above, the half-wave rectifier 52 does not generate any appreciable heat when it is connected into the electric circuit. This rectifier, moreover, is extremely compact and small in size so as to enable it to be mounted in most types of wall switching units.

The invention provides, therefore, an improved illumination control mechanism for a standard electric lamp. The mechanism of the invention requires merely an additional switch contact and a rectifier. By the use of these simple components, two distinct levels of illumination may be conveniently achieved.

The assembly of the invention is completely safe in its operation and does not consume any additional power. Moreover, the assembly does not create a fire hazard. Finally, the system and assembly of the invention is simple in its construction and relatively inexpensive.

Although the now preferred embodiment of the present invention has been shown and described herein, it is to be understood that the invention is not to be limited thereto, for it is susceptible to changes in form and detail within the scope of the appended claims.

I claim:

1. An electric lamp switching mechanism controllable to provide at least two distinct illumination levels for a single-element electric lamp having first and second terminals and controlled thereby, said mechanism including: a supporting housing, circuit means in said housing for supplying alternating current from an alternating current source to the first and second terminals of the single-element electric lamp, diode half-wave rectifier means supported in the housing to be selectively connected into said circuit means between the source and the lamp to provide half-wave rectification of the alternating current supplied from the source to the electric lamp, and switching means mounted in the housing for selectively connecting said diode rectifier means into said circuit means between the source and the lamp to provide a first illumination level for the lamp for one operating condition of the switching means and to provide a second illumination level for the lamp for a second operating condition of the switching means, the electric power supplied to the lamp at one illumination level being essentially one-half the power supplied to the lamp at the other illumination level.

2. An electric lamp switching mechanism controllable to provide at least two distinct illumination levels for a single-element electric lamp having first and second terminals and controlled thereby, said mechanism including: a supporting housing, first and second input terminal means supported on said housing adapted to be connected to an alternating current source, circuit means in the housing connected to said first and second input terminal means for establishing electrical connection to the first and second terminals of the single-element electric lamp, diode half-wave rectifier means to be selectively connected into said circuit means between the source and the lamp to provide half-wave rectification for the alternating current supplied from the source to the electric lamp, and switching means in the housing having one operating condition for connecting the lamp directly to said input terminal means and having a second operating condition for connecting said diode rectifier means into said circuit means between the source and the lamp to provide a first illumination level for the lamp for the first operating condition of the switching means and to provide a second illumination level for the lamp for the second operating condition of the switching means, the electric power supplied to the lamp at one illumination level being essentially one-half

75

the power supplied to the lamp at the other illumination level.

3. An electric lamp switching mechanism controllable to provide at least two distinct illumination levels for a single-element electric lamp having first and second input terminals and controlled thereby, said mechanism including: a receptacle, a pair of input terminals on the receptacle adapted to be connected to an alternating current source, circuit means, an electric lamp socket supported in the receptacle having one terminal connected by the circuit means to one of said input terminals and having a second terminal connected to the circuit means, a diode half-wave rectifier mounted in said receptacle to be selectively connected into said circuit means between the source and the lamp to provide half-wave rectification of the alternating current supplied from the source to the electric lamp, said diode half-wave rectifier having a first terminal connected to the second terminal of the lamp by said circuit means and having a second terminal, and a switch mounted in said receptacle having an armature connected to the other one of said input terminals by said circuit means and having a first fixed contact connected to the second terminal of the lamp by said circuit means and having a second fixed contact connected to the second terminal of said rectifier by said circuit means to provide a first illumination level for the lamp when the armature engages the first fixed contact and to provide a second illumination level for the lamp when the armature engages the second fixed contact, the electric power supplied to the lamp at one illumination level being essentially one-half the power supplied to the lamp at the other illumination level.

4. An electric lamp switching mechanism controllable to provide at least two distinct illumination levels for a single-element electric lamp controlled thereby, said mechanism including: a receptacle, a pair of input terminals on the receptacle adapted to be connected to an alternating current source, circuit means in said receptacle for supplying electric energy from the alternating current source to the single-element electric lamp, said circuit means having one terminal connected to one of said input terminals and having a second terminal, a diode half-wave

rectifier mounted in said receptacle to be selectively connected into said circuit means between the source and the lamp to provide half-wave rectification of the alternating current supplied from the source to the electric lamp, said half-wave rectifier having a first terminal connected to the second terminal of said circuit means and having a second terminal, a first switch mounted in said receptacle connected between the second terminal of said half-wave rectifier and the other one of said input terminals by said circuit means, and a second switch mounted in said receptacle connected across said half-wave rectifier to provide a first illumination level to the lamp when both the first and second switches are closed and to provide a second illumination level for the lamp when the first switch is closed and the second switch is open, the electric power supplied to the lamp at one illumination level being essentially one-half the power supplied to the lamp at the other illumination level.

5. In an electric unit system for providing at least two distinct energization levels for an electric unit controlled thereby, the combination of: circuit means for supplying alternating current from an alternating current source to the electric unit, rectifier means to be selectively connected into said circuit means between the source and the unit to provide rectification of the alternating current supplied from the source to the electric unit, and switching means for selectively connecting said rectifier means into said circuit means between the source and the unit to provide a first energization level for the unit for one operating condition of the switching means and to provide a second energization level for the unit for a second operating condition of the switching means, the electric power supplied to the unit at one energization level being less than that supplied to the unit at the other energization level.
